UNITED STATES PATENT OFFICE.

CHARLES F. COOK, OF HOUSTON HEIGHTS, TEXAS.

COOKING-STOVE.

1,297,545.

Specification of Letters Patent. Patented Mar. 18, 1919.

Application filed February 26, 1917. Serial No. 150,993.

To all whom it may concern:

Be it known that I, CHARLES F. COOK, a citizen of the United States, residing at Houston Heights, in the county of Harris 5 and State of Texas, have invented certain new and useful Improvements in Cooking-Stoves, of which the following is a specification.

This invention relates to new and useful 10 improvements in cooking stoves.

The object of the invention is to provide a stove of the character described provided with an oven, and a combustion chamber, so arranged relative to each other, that the 15 heat will completely surround said oven, said stove being equipped with a novel form of oil burner which is contained in the combustion chamber and adapted to utilize oil as a fuel.

With the above and other objects in view 20 the invention has particular relation to certain novel features of construction, arrangement of parts, and use, an example of which is given in this specification and illustrated 25 in the accompanying drawing wherein:—

Figure 1, is a vertical sectional view of the stove.

Fig. 2, is a side view of the burner.

Fig. 3, is a plan view thereof, and

Fig. 4, is an end view of the blaze deflectors.

Referring now more particularly to the drawings wherein like numerals of reference designate similar parts in each of the 35 figures, the numeral 1 refers to the body or outer shell of the stove which is composed usually of sheet metal, and, as shown, has the top, bottom, front, rear, and end walls, but may be formed into any particular design 40 desired. The numeral 2 designates the oven whose top, bottom and front and rear walls are spaced from the corresponding outer walls of the stove body, forming the flue 3 on all sides of said oven, and whose 45 ends are formed by the ends of the stove body to which the respective ends of the oven are secured. This oven is provided for use in baking or cooking articles which are placed therein and is usually formed of 50 suitable sheet metal.

A transverse partition 4, is provided between the oven and the top of the stove and extends entirely across from end to end of the stove. Behind this partition is the pipe

5 from which the smoke is discharged from 55 the flue 3, and in front of said partition is the combustion chamber 6.

A transverse apron 7 is provided in front of the combustion chamber, extending from end to end of the stove entirely across, said 60 apron restricting the flue 3 and deflecting the flame up toward the top of the stove.

A burner is provided which is formed of two parallel pipe sections 8, 8 connected together at one end by a suitable connection 9. 65 The upper sides of these pipe sections 8, 8 have perforations as 10, forming discharge orifices through which the fuel oil is discharged. This burner is arranged transversely in the combustion chamber and rests 70 upon the oven and the fuel is admitted to it through the pipe 11 which leads from the fuel oil tank 12 and is controlled by the gate valve 13 provided to entirely cut off the fuel when the stove is not in use and 75 the needle valve 14 provided to regulate the flow of fuel to the burner.

A deflector support 15 is provided, one end of which is attached to, and supported by, the foot piece 16 and the other end 17, 80 of which is formed to fit the contour of the transverse section of the pipe 11 and is supported thereby, said support being spaced above the burner. Fixed to the deflector support and alined above the discharge perforations 10 are the flame deflectors 18 which are arcuate in form and which serve to spread the flames and distribute them over the top of the stove so as to supply uniform heat to the cooking utensils on the stove. 85 90

A stove constructed in accordance with the foregoing specification and the drawings accompanying the same, will be found to be very economical in the consumption of fuel and will distribute the heat uniformly around the oven thus forming a superior cooking stove particularly for baking purposes. At the same time on account of the circulation and distribution of the heat around the stove walls the stove will 95 100 radiate heat and may be used as a combination cooking and heating stove.

What I claim is:

A stove whose walls are formed of sheet metal, an oven formed of top, bottom, front 105 and rear walls extending from end to end of the stove but spaced from the corresponding walls forming a flue around the oven, a

transverse partition between the top of said oven and the top of the stove, a smoke outlet communicating with the flue on one side of said partition, a combustion chamber on 5 the other side of said partition, the top of the oven forming the bottom wall of the combustion chamber and an apron arranged in front of the combustion chamber and forming the front wall thereof provided to

restrict the flue and deflect the blaze up 10 against the top of the stove.

In testimony whereof I have signed my name to this specification in the presence of two subscribing witnesses.

CHARLES F. COOK.
